(57) CLAIM

The ornamental design for a garment with back opening, as shown and described.

DESCRIPTION

FIG. 1 is a front, perspective view of a garment with back opening showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the garment with back opening and form no part of the claimed design. The long dash-short dash bolded broken lines indicate the bounds of the claimed design and otherwise form no part of the claimed design.
